POWER OPERATED CUTTER

Vladimir S. Nerty, 160 Dewitt St., New Haven, Conn.
Filed Aug. 12, 1963, Ser. No. 301,421
3 Claims. (Cl. 30—228)

My invention relates to power operated cutting devices and more particularly to power operated devices used for the cutting of cables, rods and the like.

One of the important objects of my invention is to provide a power operated cutter which can develop ample force to cut strong cables and bars and which can be operated very conveniently even in confined quarters where with the customary hand tools the cutting work would be very difficult and slow, if not impossible.

Another important object of my invention is to provide a power operated cutter which may be operated equally well by an electric, pneumatic or hydraulic motor and thereby can be easily adapted to particular working conditions.

A further object of my invention is to provide a power operated cutting tool which is reliable in operation and can be manufactured economically.

Other objects and advantages of my invention will be apparent during the course of the following description.

In the accompanying drawing forming a part of the present application, wherein, for the purpose of illustration is shown a preferred form of my invention,

FIGURE 1 is a longitudinal sectional view of the preferred form of my power operated cutter,

FIGURE 2 is a top view of the cutting blade and the connected plunger screw,

FIGURE 3 is a cross sectional view taken on the line 3—3 of FIGURE 1.

Referring to FIG. 1 of the drawing, the body or frame of my power operated cutter is composed of a tubular rear portion 1 and a hook shaped front portion 2 provided with a cavity for receiving the object to be cut, and an internal fixed cutting edge. Part of said front portion 2 of the body is covered by the cover 3, secured by bolts, and having space between them for the disposition of a slidable cutting blade 5 which, in the form illustrated, has a slanting sharp cutting edge which may be brought into cutting relation with said fixed cutting edge of said front portion 2. The alternating sliding motion of the cutting blade 5, necessary for the cutting operation, is accomplished by means of the plunger screw 8, which is non-rotatable and having at its front end a rectangular head 9, which is secured to said cutting blade 5, and is provided with a threaded portion 10 adjacent to its rear end. The cutting blade 5 is provided with a rectangular opening 6, adjacent to the rectangular head 9, for the mounting of the front buffer spring 7, which is secured to said head 9. The top view of this assembly of the cutting blade, plunger screw and front buffer spring is shown in FIG. 2.

The rectangular head 9 and the connected front buffer spring 7 are slidable within the passage 4, which is formed by two opposing grooves, as shown in FIG. 3. It is essential in this invention that the front end of this passage 4 is so located that it engages the spring 7 before the extreme front position of the cutting blade 5 and the connected parts is reached, with the result, that this spring 7 will be compressed in this extreme front position of the cutting blade and the connected plunger screw 8.

Mounted within the tubular rear body portion 1 is the cylindrical sleeve 11, which is rotatably supported and axially retained by the ball bearings 12 and 13 and is provided with a drive end 15 to be connected to a reversible motor 17, which may be electric, pneumatic or hydraulic. The numeral 18 represents the handle of the device.

2

The cylindrical sleeve 11 has an internal threaded portion 14 designed to cooperate with the threaded portion 10 of the plunger screw. Mounted inside the sleeve 11 is the rear buffer spring 16, which is so positioned that it is compressed by the end of the plunger screw 8 in the extreme rear position of this screw and the connected cutter blade 5.

It is essential in this invention that the cooperating threaded portions 10 and 14 of the screw and the sleeve, respectively, are so dimensioned that in the extreme front position of the screw and the connected parts the threaded portion 10 moves out of engagement with the threaded portion 14 so that the sleeve 11 may continue its previous rotation without further advancing the screw and the connected parts. Similarly, in the extreme rear position of the screw and the connected parts the threaded portion 10 moves out of engagement with the threaded portion 14 in the opposite direction so that the sleeve may continue its rotation without further withdrawing the screw and the connected parts.

The operation of my device is as follows: The object to be cut is placed into the hook shaped cavity against the fixed cutting edge; the movable cutting blade 5 being withdrawn. Then, the reversible motor is started to rotate the sleeve 11 in the direction in which the screw and the connected cutting blade advance toward the fixed cutting edge. As this movement continues the front end of the buffer screw 7 will contact the end of the passage 4, so that the further advance will compress the spring 7. When the cutter blade 5 and the connected parts reach the extreme front position the threaded portions of the screw and the sleeve disengage, permitting the sleeve to continue its previous rotation without further advancing the cutter blade and the connected parts and without overloading the driving motor. The movement of the cutter blade is so designed that in the extreme front position of the cutting blade the cutting operation is completed.

The next step is the withdrawal of the cutting blade. This is accomplished by reversing the rotation of the driving motor. Due to axial pressure exerted by the compressed spring 7 at the reversed rotation of the sleeve 11 the threaded portion 10 and 14 will engage causing the withdrawal of the cutting blade by the plunger screw 8. This rearward motion will continue until the cutting blade and the connected screw 8 reach the extreme rear position, when the threaded portions 10 and 14 again disengage preventing a further rearward motion of the cutting blade and the connected parts if the motor 50 continue to run. Then, the cutting operation being completed the motor may be deenergized. As in this extreme rear position the rear buffer spring 16 is compressed, the threaded portions 10 and 14 will engage automatically as soon as the motor is started in the reverse direction to advance the cutting blade 5 for another cutting operation.

It is to be understood that the form of my invention herein described and illustrated is only an example of the same, and that various changes in the size, shape and in the arrangement of parts may be resorted to, without departing from the spirit of my invention or the scope of the subjoined claims.

I claim:

1. A power operated cutter comprising a body having a hook shaped cavity with an internal fixed cutting edge; a cutting blade slidable within said body in cutting relation with said fixed cutting edge; a plunger screw attached to said cutting blade and having a threaded portion; a front buffer spring secured to the front end of said plunger screw; a sleeve rotatable and axially retained within said body and being operatively connected to a reversible power driving means, said sleeve contains a

rear buffer spring and being provided with internal threaded portion adapted to cooperate with the threaded portion of said plunger screw, said threaded portions and buffer springs being so adapted that at one direction of rotation of said sleeve said screw and cutting blade advance toward said fixed cutting edge until the rear thread of the screw passes the front thread of said sleeve and said front buffer spring is compressed, in which position the sleeve may continue its rotation in the same direction without further advancing said screw and blade, at opposite direction of rotation of said sleeve, due to the pressure of said compressed front buffer spring said threads engage causing the withdrawal of said screw and cutting blade until the front thread of the screw passes the rear thread of the sleeve and said rear buffer spring is compressed, in which position the sleeve may continue its rotation in the same direction without further withdrawing the screw and blade, and at another reversal of the rotation of the sleeve, due to the pressure of the contracted rear buffer spring, said threads engage so as to advance the screw and blade toward said fixed cutting edge.

2. A power operated cutter comprising a body having a hook shaped fixed cutting edge; a cutting blade slidably mounted within said body; a plunger screw secured to said cutting blade and having a threaded portion; a sleeve rotatably mounted in said body retained against axial movement and having an internal threaded portion for cooperation with the threaded portion of said screw, said cooperating threads being so adapted that at one direction of rotation of said sleeve said cutting blade and screw advance toward said fixed cutting edge to the extreme front position where the threaded portion of the screw passes out of engagement with the threaded portion of said sleeve and at the opposite direction of rotation of said sleeve said cutting blade and screw are withdrawn from said cutting edge until they reach the extreme rear position where the threaded portion of the screw passes out of engagement with the threaded portion of said sleeve; a front buffer spring adapted to be

compressed by the advancing plunger screw in its extreme front position exerting axial pressure on said plunger screw for the engagement of said threaded portions when the rotation of said sleeve is reversed; a rear buffer spring adapted to be compressed by the withdrawn plunger screw in its extreme rear position exerting axial pressure on said plunger screw for the engagement of said threaded portions when the rotation of said sleeve is reversed; reversible driving means with power supply for the rotation of said sleeve.

10 3. A power operated cutter comprising a body; a fixed cutting edge and a movable cutting blade on said body; a plunger screw secured to said cutting blade and having a threaded portion; a sleeve reversibly rotatable on said body, retained against axial movement, and having a threaded portion for cooperation with the threaded portion of said screw, so adapted that, at one direction of rotation of said sleeve said cutting blade and screw are advanced toward said fixed cutting edge into their extreme front position where the threaded portion of the screw moves out of engagement with the threaded portion of said sleeve and at the opposite direction of rotation of said sleeve said cutting blade and screw are withdrawn from said fixed cutting edge into their extreme rear position where the threaded portion of the screw moves out of engagement with the threaded portion of said sleeve; a pair of buffer springs, so adapted that one is compressed in the extreme front position, the other in the extreme rear position of said plunger screw, providing pressures to facilitate the reengagement of said cooperating threaded portions at the reversal of the rotation of said sleeve; reversible driving means with power supply for the rotation of said sleeve.
